(57) **CLAIM**

The ornamental design for an antenna, as shown and described.

DESCRIPTION

FIG. 1 is a front elevation perspective view of an antenna showing our new design;

FIG. 2 is a first side elevation view of FIG. 1;

FIG. 3 is second side elevation view of FIG. 1;

FIG. 4 is third side elevation view of FIG. 1;

FIG. 5 is fourth side elevation view of FIG. 1;

FIG. 6 is a top plan view of FIG. 1;

FIG. 7 is a bottom plan view of FIG. 1;

FIG. 8 is a perspective view of the antenna, shown with parts separated for ease of disclosure; and,

FIG. 9 is a side view of the antenna, shown with parts separated for ease of disclosure.

The broken lines are shown for environmental purposes and form no part of the claimed design.
